CLAIM

The ornamental design for a electrical muscle stimulation sleeve, as shown and described.

DESCRIPTION

FIG. 1 is an isolated perspective view of the electrical muscle stimulation sleeve, showing the new design; FIG. 2 is a front elevational view of the electrical muscle stimulation sleeve thereof;

FIG. 3 is a rear elevational view of the electrical muscle stimulation sleeve thereof;

FIG. 4 is a right side elevational view of the electrical muscle stimulation sleeve thereof;

FIG. 5 is a left side elevational view of the electrical muscle stimulation sleeve thereof;

FIG. 6 is a top plan view of the electrical muscle stimulation sleeve thereof; and,

FIG. 7 is a bottom plan view of the electrical muscle stimulation sleeve thereof.

The broken lines shown in FIGS. 1-7 illustrate portions of the electrical muscle stimulation sleeve that form no part of the claimed design. The additional broken lines in FIG. 8 illustrate environment that form no part of the claimed design.
